No. 643,683.

Patented Feb. 20, 1900.

W. M. REID.
MEASURING VESSEL.

(Application filed July 15, 1899.)

(No Model.)

UNITED STATES PATENT OFFICE.

WILLIAM M. REID, OF BISHOPVILLE, SOUTH CAROLINA.

MEASURING VESSEL.

SPECIFICATION forming part of Letters Patent No. 643,683, dated February 20, 1900.

Application filed July 15, 1899. Serial No. 723,966. (No model.)

To all whom it may concern:

Be it known that I, WILLIAM M. REID, a citizen of the United States, residing at Bishopville, in the county of Sumter and State of 5 South Carolina, have invented a new and useful Improvement in Measuring Vessels, of which the following is a specification.

My invention relates to vessels for holding and dispensing rice, grist, or like substances, 10 the object of the invention being to provide for merchants and the public in general a vessel of this class which by virtue of its improved construction will be adapted for holding a quantity of such substances and dis- 15 charging a predetermined quantity therefrom with great accuracy, avoiding the necessity of measuring each quantity discharged in cups or other measures, and thus economizing in time and labor.

20 With this object in view my invention consists in the improved construction, arrangement, and combination of parts hereinafter fully described and afterward specifically pointed out in the claims.

25 In order to enable others skilled in the art to which my invention most nearly appertains to make and use the same, I will now proceed to describe its construction and operation, reference being had to the accompanying 30 drawings, forming part hereof, in which—

Figure 1 is a view in side elevation of a vessel embodying my invention, the upper part being broken away and parts shown in dotted lines. Fig. 2 is a sectional view through the 35 discharge-spout and the outer valve and cylinder on the plane indicated by the broken line 2 2 of Fig. 1. Fig. 3 is a sectional view on the plane indicated by the broken line 3 3 of Fig. 2. Fig. 4 is a transverse sectional view 40 on the plane indicated by the broken line 4 4 of Fig. 3. Fig. 5 is a detail perspective view of the piston-head detached. Fig. 6 is a fragmentary detail sectional view of part of the inner cylinder therein.

45 Like numerals of reference mark the same parts wherever they appear in the several figures of the drawings.

Referring to the drawings by numerals, 7 indicates a can or vessel of any suitable shape 50 in cross-section, provided with a false bottom 8, as shown in dotted lines in Fig. 1, said false bottom being so shaped as to conduct the con-

tents of the can into a downwardly-inclined discharge tube or spout 9. Upon the discharge-spout and at right angles thereto are 55 erected a plurality of valve-cylinders, as at 10, 11, and 12, three being shown in this instance, although any number from two up may be used, according to circumstances or the desire of the manufacturer or user. These 60 valve-cylinders and their valves and operating mechanisms are all alike and a detailed description of one will apply to any other.

13 indicates an inner cylinder having notches 14 to receive wings 15 on a diaphragm 65 16, fitted within the main cylinder 11, the disk having a central opening 17 and the cylinder having a cover 18 with a larger central opening 19.

20 indicates a plunger-rod of two diameters, 70 the larger to fit opening 19 and the smaller to fit opening 17, a shoulder 21 being formed at the junction of the two parts of the rod. The inner end of the rod passes through the disk and between the disk and the shoulder 21 a 75 spring 22 is coiled around the rod and has a normal tendency to force the rod outward. A head 23 is secured to the inner end of the rod and has two rounded ends to fit in the cylinder. In the bottom of the head is a groove 80 24, into which a valve 25 is fitted and secured by screw 26. The valve is of a size to fit across and close the discharge-spout 9, and of a consequence is wider than the valve-cylinder and projects laterally through slots 27 therein, as 85 well as through slots 28 in the upper half of the discharge-spout when the valve moves down. To prevent the head 23 from turning and to guide it in its reciprocation, a screw 29 is projected into one of the slots 27. 90

30 indicates a stop or latch lever pivoted to the outside of the cylinder above the slots 27 and provided with a notch 31 in its lower end to fit over the screw 29 when in its lower position. A screw 32 prevents the stop-lever 95 from being pushed beyond the line of the slots 27.

In the practical operation of the invention the lower valve in cylinder 12 is normally closed, so that the contents of the can will 100 fill the discharge-spout from that valve upward. The valves are so placed in the spout that the length of spout between two adjacent valves will hold a given quantity—say one

pint. To discharge a pint from the spout, the valve in cylinder 13 is pressed down or closed and locked by its stop-lever. The lower valve is now opened and the pint of material 5 below the second valve allowed to flow out, after which the lower valve is again closed and locked and the stop-lever of the second valve released, permitting its spring to raise the valve and again filling the spout down to 10 the lower valve ready for another operation. Should a quart be desired, the upper valve will be manipulated, as before described, instead of the lower valve.

The simplicity, utility, and time and trouble saving virtues of my invention will be obvious from the foregoing description and need 15 no further elucidation.

Having thus fully described my invention, what I claim as new, and desire to secure by 20 Letters Patent of the United States, is—

1. In a measuring vessel, the combination with a can and a discharge-spout having side slots, of a valve-cylinder of less diameter than the spout secured thereto and provided with 25 side slots in line with those of the spout, a head fitted to slide in the cylinder, a screw passed through one of the cylinder-slots into the head, a valve secured in the bottom of the head and projecting through the side slots, 30 a spring for holding the head outward, and

a latch for locking it inward by engagement with the guide-screw, substantially as described.

2. In a measuring vessel, the combination with a valve-cylinder, an inner cylinder there- 35 in having notches in its upper end, a disk in the cylinder having wings engaging in the notches and a central opening, a lid having a larger central opening, a plunger-rod of two diameters fitting in the openings in the disk 40 and lid, a spring coiled around the smaller portion of the rod between the disk and the larger portion, a head secured to the rod below the disk and having a groove in its under face, and a valve secured in said groove, sub- 45 substantially as described.

3. The combination with a valve-cylinder, having side slots, of a plunger-head in the cylinder, a spring for retracting it, a screw projected through one of the slots into the 50 head, a valve carried by the head, a latch or stop lever pivoted to the outside of the cylinder above and in line with the slots having a notched end to engage the screw to hold the head against the action of the spring, and a 55 stop for the lever, substantially as described.

WILLIAM M. REID.
